UNITED STATES PATENT OFFICE.

ALLEN F. ADAMS, OF MADRID, IOWA.

ACETYLENE MINER'S LAMP.

1,238,729.

Specification of Letters Patent.

Patented Sept. 4, 1917.

Application filed September 6, 1916. Serial No. 118,746.

To all whom it may concern:

Be it known that I, ALLEN F. ADAMS, a citizen of the United States, residing at Madrid, in the county of Boone and State 5 of Iowa, have invented certain new and useful Improvements in Acetylene Miners' Lamps, of which the following is a specification.

My invention relates to new and useful 10 improvements in acetylene miners' lamps, the primary object of my invention being the provision of a lamp of the above character having a supplemental gas generating chamber which may be filled independently 15 of the lamp proper and from which a pipe leads to a burner disposed in proximity to the main burner of the light so that when gas is generated in the supplemental chamber it will be ignited at the supplemental 20 burner from the flame of the main burner.

Another object of my invention consists in forming the supplemental generator in the form of a cylindrical chamber having a removable cap, the cylinder being adapted 25 to receive both the carbide and the water necessary for the generation of the acetylene gas and the cap being provided with a strainer for preventing the passage of impurities from the generating chamber to the 30 supplemental burner.

In this connection another object which I have in view is the provision of a novel and simple means for connecting the strainer to the cap.

With these and other objects in view my invention will be more fully described, illustrated in the accompanying drawings and then specifically pointed out in the claim which is attached to and forms a part of this 35 application.

In the drawings:

Figure 1 is a perspective view of a conventional form of acetylene lamp particularly adapted for miners' use showing my 40 invention applied thereto;

Fig. 2 is a fragmentary elevational view showing my supplemental generator in section;

Fig. 3 is a perspective view of the generator separated from the lamp proper showing the cover in partially removed position;

Fig. 4 is a transverse sectional view taken on the line 4—4 of Fig. 2.

In order to insure a clear and accurate 50 understanding of my invention, I have illus-

trated it in connection with a conventional form of miner's lamp including the carbide holding receptacle 10, the water chamber 11 which has threaded connection with the carbide receptacle as shown at 12 and which has the usual filling spout 13. The feed of water from the chamber 11 to the receptacle 10 is controlled by a valve, the stem of which is shown at 14, in the usual manner and the 60 lamp is provided with a suitable bracket 15 by means of which it may be attached to a miner's cap. The main burner 16 of the lamp extends centrally through a circular reflector 17 and disposed adjacent it is a 70 mechanical lighting device 18 of any suitable type.

As now placed upon the market when either water or carbide is exhausted the lamp must be extinguished while a fresh supply 75 of either water or carbide or both is supplied. It is therefore oftentimes necessary for a miner when working alone to renew his water or carbide supply in the dark with the result of a considerable loss of time and 80 trouble. To avoid this I provide a supplemental burner 19 which I locate adjacent the main burner 16 and a supplemental generator indicated as a whole by the numeral 20 for supplying acetylene gas to the supplemental burner. This generator in the 85 present instance is of cylindrical formation including the body 21 having a closed bottom 22, the body being soldered, brazed or otherwise secured to the water chamber 11 90 of the lamp immediately at the rear of the reflector 17. This body is open at its upper end and at such end is internally threaded to receive the threaded annular flange 23 of a cap 24. This cap 24 is also provided with 95 a peripheral stop flange 25 to insure a close sealing and is provided centrally with a swivel eye 26 to receive one end of a chain 27 the opposite end of which may be correspondingly anchored to the lamp. By 100 this means loss of the cap during filling of the supplemental generator is avoided. The threaded flange 23 is of considerable length and at its free edge is incrimped as shown at 28 to engage a cylindrical plug of felt 29 105 or other suitable material which extends throughout substantially half the length of the generator when the cap is in place. A pipe 30 leads from the generator adjacent the lower end of the flange 23 through the 110 reflector to the burner 19.

In operation, when it becomes necessary

to renew the supply of water, carbid or both in the lamp, the miner first removes the cap 24 of the supplemental generator and then places one or more pieces of carbid in the 5 bottom of the generator and adds a small quantity of water, immediately replacing the cap. The carbid and water thus brought together in the supplemental generator react to produce acetylene gas which passes 10 through the plug or filter of felt 29 through the pipe 30 to the burner 19 at which point it is ignited by the flame from the main burner 16. The carbid holding receptacle of the lamp proper may then be removed 15 and its supply of carbid replenished by the light given off from the supplemental burner 19. Obviously the supplemental generator need not be of very large dimensions and in some instances, if preferred, its body portion may be inclosed in the water chamber 20 of the lamp proper and its cap merely exposed through the top of such chamber. It

will therefore be clear that I do not wish to in any way limit myself to specific details of construction illustrated and described but 25 reserve the right to make any changes within the scope of the appended claim without in the slightest degree departing from the spirit of my invention.

Having thus described my invention, what 30 I claim as new is:

An attachment for acetylene miners' lamps including a casing adapted for connection to the exterior of a miner's lamp, the casing being open at one end, a closure 35 for such end of the casing having a flange projecting within the casing, a plug of absorbent material secured to the closure by the flange and projecting into the casing, and a pipe leading from the casing with one 40 end covered by the plug and the opposite end adapted to receive a burner.

In testimony whereof I affix my signature.

ALLEN F. ADAMS. [L.S.]
